UNITED STATES PATENT OFFICE.

FREDERICK HANDLEY PAGE, OF LONDON, ENGLAND, ASSIGNOR TO HANDLEY PAGE LIMITED, OF LONDON, ENGLAND.

METHOD OF AND MEANS FOR CONTROLLING AEROPLANES.

Application filed July 11, 1924, Serial No. 725,426, and in Great Britain July 18, 1923.

It has long been common knowledge that in the lateral control of aeroplanes during flight, it was necessary not merely to adjust the degree of camber or angle of incidence of the extremities of the wings, to give the required righting rolling movement, but also simultaneously to operate a vertical rudder on the tail of the machine. Such simultaneous rudder movement produces a turning movement about a vertical axis to balance the yawing moment caused by the difference in resistance of the said wing extremities when so adjusted. This resistance difference is mainly due to the fact that with aircraft as now built, the increased lift (necessary for the required righting rolling moment) obtained by the increase in camber or angle of incidence, is accompanied by a simultaneous resistance increase and vice versa. It has also been proposed to introduce resistances on or near the ends of the wings for the purpose of counterbalancing head resistance changes in the ends of the wings, and thus by introducing extra resistance to prevent the operation of the ailerons from turning the machine about a vertical axis while restoring lateral equilibrium.

This invention relates to means for maintaining and restoring lateral balance on an aeroplane, without simultaneously causing an excessive resistance difference between the two wing extremities. Thus by reducing greatly the turning or yawing moment of the aeroplane as a whole about a vertical axis, an increase in lateral control may be obtained, especially at slow speeds, with a minimum use of the vertical rudder.

In the specification of an earlier patent I have described the use of an auxiliary wing located in front of the wing of an aeroplane, for the purpose of increasing the lift by delaying the burbling effect over the upper surface of an aeroplane when the flying angle has increased. This permits the lift on the aerofoil to continue to increase in value with increase in the angle of incidence up to a higher angle when burbling again ensues. The delay in burbling due to the operation of this forwardly located auxiliary wing, has permitted wings to be employed at much greater angles of incidence than previously. It is obvious, however, that with the increased angle of attack, the head resistance is increased simultaneously with the gain in lift of the wing, but

such increase is less than would have occurred at the same angle of incidence had the wing been burbling. If burbling were therefore re-introduced, diminished lift and similar or increased resistance would result. This effect being the reverse of that obtained by alteration of wing camber or angle of incidence, it is possible so to combine the two as to produce a righting rolling moment without a simultaneous excessive yawing moment.

Now the present invention relates to means whereby burbling may be introduced over the wing or wings, on one side of the machine, for the purpose of reducing the lift on one wing compared to that on the other wing without materially changing the head resistance of one wing relatively to the other, thus permitting the two wings to be kept in balance without continual co-operation of the vertical rudder.

The invention therefore refers to laterally controlling aeroplane flying machines which have wings projecting laterally from opposite sides of a central fuselage, said wings having forwardly located auxiliary wings separated from said main wings to produce through slots, and according to the present invention means are provided for regulating the flow of air through said slots in the wings on one side of said fuselage, and other separately operable means for regulating the flow of air through said slots in the wings on the other side of the fuselage. Thus by so disturbing the flow of air through said slots as to deprive or partially deprive the upper surface of the wing of air which when flowing through said slots would prevent or minimize burbling, burbling is therefore permitted to take place to any required extent, thereby depriving say the higher wing of a portion of its support; the said higher wing therefore becomes depressed and the lower wing raised relatively thereto, thus restoring the lateral balance of the machine.

In carrying out the invention the aileron on each wing of the machine may be in operative mechanical connection with the portion of the auxiliary wing immediately in front of it; or the aileron may be connected to some part which controls the extent of the opening of the slot between the outer portion of the auxiliary wing and the main wing. Or interceptor flaps in oper-

ative connection with the ailerons may be located in or near the slot, or over the main wing, which interceptor flaps can be caused to interfere with the flow of air between the auxiliary wing and the main wing, or over the main wing and either change its direction away from the burbling area, or check the flow of air through the slot.

The invention will be more particularly described with reference to the accompanying drawings, which show in diagrammatic form, various examples of means which may be employed for introducing burbling for controlling aeroplanes in accordance with this invention.

One mechanism which permits this effect to be attained, consists in connecting the aileron with the forwardly located wing by means of a mechanical connection having a lost motion, which mechanism leaves the aileron free to be lowered in its ordinary movements, but when raised above its normal position for horizontal flight, operates to move the forwardly located wing either to close or reduce the opening between it and the main wing, or to increase the opening to an abnormal extent and cause the upper surface of the auxiliary wing to be presented to the air flow.

In Figs. 1, 2 and 3, the main wing 1 has an auxiliary wing 2 located in front of it, and the aileron 3 is connected with the auxiliary wing by a rod 4, one end of which is pivoted at 5 to an arm 6 carried by the wing 2; the other end of the rod passes freely through an eye or socket carried by the aileron 3, a stop 7 being fixed on the rod 4. By this means the aileron 3 is free to be lowered in its ordinary movements below its normal position without affecting the auxiliary wing 2 (see Fig. 2), while an upward movement of the aileron above the normal lowers the auxiliary wing and closes the slot (see Fig. 3).

Figs. 4, 5 and 6 show similar views, the connecting rod 4 being so arranged that the raising of the aileron above the normal position raises the auxiliary wing 2 abnormally and causes it to present its upper surface to the air flow (see Fig. 6).

By another means the levers or mechanism operating the ailerons and the forwardly located wing respectively, may be so angularly placed or so altered relatively in phase, that the movement given to the forwardly located wing is practically nil when the aileron is moved downward below the neutral position, but the full required movement is obtained with the upward aileron movement when moved above the normal position.

Fig. 7 illustrates an example wherein the forwardly located wing may be raised to an abnormal extent (see dotted lines 2*) by the upward movement of the aileron to its normal full extent, while the downward move-

ment of the aileron below the normal position gives but a slight downward movement to the forwardly located wing (see dotted lines 2**).

Another method of introducing burbling, 70 is by the connection of the aileron to interceptor flaps contained in the slot or near the slot, or over the auxiliary or over the main wing, which interfere with the flow of air between the auxiliary wing and the main 75 wing, or over the main wing or auxiliary wing, and either change its direction away from the burbling area or check the flow of air through the slot.

Figs. 8, 9 and 10 show interceptor flaps 80 pivoted on the main wing and capable of adjustment to restrict or close the opening between the wings 1 and 2.

Fig. 11 shows an interceptor 8 in its raised position pivoted on the main wing 1 rearward of the slot, and Fig. 12 shows an interceptor 8 pivoted above the main wing and rearward of the slot, both of which interceptors can be adjusted, to allow a free flow of air through the slot between the wings 90 1 and 2 and over the main wing, or to change the direction of flow away from the upper surface of the main wing.

These interceptors or fouling devices may take the form of louvres or small vanes turning on hinges or fulcrums near the slot, or they may be entirely separate fouling devices placed for instance on the surface of the main wing some distance back from the slot, or on the auxiliary wing some distance in front of the slot, and by turning on a horizontal or vertical axis, or axes in the case of a number of fouling devices, intercept the air flowing to the burbling area and induce burbling with consequent loss of lift.

Examples of such interceptors are shown at Figs. 13 to 18. Fig. 13 shows the forward portion of the main wing having an interceptor 9 mounted on the main wing and capable of turning on a vertical pivot indicated by a dotted line 10. Fig. 14 is a similar view with the interceptor 9 turned on its pivot 10 into position to intercept the air flowing to the burbling area and induce burbling with consequent loss of lift.

Fig. 15 shows a vane 11 mounted in the main wing and pivoted on a horizontal axis 12, and Fig. 16 is a view at right angles to Fig. 15. The vane 11 is shown in its raised position to obstruct the flow of air over the main plane, and when not required the vane is lowered into a recess in the wing, hinging on the pivot 12.

Figs. 17 and 18 show in elevation and plan view a portion of the main plane 1 and auxiliary plane 2, the main plane having upon its upper surface a series of vanes 13 of stream-like form in cross section and capable of being turned on vertical axes, as indicated by the dotted arcs 14, to more or less 130

obstruct the flow of air and cause burbling on the upper surface of the main wing.

All these devices may be operated independently of the aileron, or be operated by 5 an upward movement of the aileron.

In Figs. 19, 20 and 21, the interceptor 9 is shown connected to the aileron 3 by a connecting rod 4 having a slot 15 formed in one end, in which slot a pin 16 engages 10 carried by the aileron on an arm 17. It will be seen that the movement of the aileron from its normal position in a downward direction does not affect the position of the interceptor owing to the lost motion allowed 15 by the movement of the pin 16 in the slot, while an upward movement of the aileron above the normal position raises the interceptor 9 and interrupts the flow of air on the upper surface of the main wing.

20 As an example of the controlling means for such fouling devices, the mechanism connecting them and the aileron may be so geared that for all downward movements of the aileron, the corresponding motion of 25 these fouling devices is contained within the wing whilst it is an abnormal upward movement only of the aileron which causes these fouling means to come into effective operation.

30 Fig. 22 illustrates an example of such mechanism. An interceptor 9 is shown, pivoted on the main wing 1 and carrying on its axis a pulley or sprocket wheel around which is passed a cable or chain fixed at its 35 ends to arms carried by the aileron 3. When the aileron is moved upwardly above its normal position, as shown, the interceptor is raised into its operative position, and when the aileron is lowered, the interceptor is 40 also lowered and passes within the wing 1.

Whilst the above has been described relatively to a wing in which there is one forwardly located auxiliary aerofoil, it is understood that it may also include and apply to 45 similar operation of rearwardly or otherwise located aerofoils, or to the opening or closing or putting out of operation of one or more slots in the wing wherever situated with respect to the chord.

50 It is of course clear that any length of forwardly located wing or length of aileron may be operated or inter-connected and moved separately to the remainder of the forwardly located wing or aileron, in order 55 that the introduction of burbling over the wings may be located as desired and to the required extent. It is also obvious that it is not necessary to introduce the disturbance merely by some movement imparted 60 by the aileron or section of the aileron immediately following the forwardly located wing, as the forwardly located wing and aileron section can be independently operated or operated in conjunction with each 65 other, as may be found most desirable.

What I claim as my invention and desire to secure by Letters Patent is:—

1. In laterally controlling aeroplane flying machines having wings projecting laterally from opposite sides of a central fuselage, 70 said wings having forwardly located auxiliary wings separated from the main wings to produce through slots; each of said slots having its opening on the under surface of the wing in advance of the opening on the 75 upper surface, means for regulating the flow of air through said slots in the wings on one side of said fuselage, and other separately operable means for regulating the flow of air through said slots in the wings on the other 80 side of the fuselage.

2. In laterally controlling aeroplane flying machines, having wings projecting laterally from opposite sides of a central fuselage, 85 said wings having forwardly located auxiliary wings separated from the main wings to produce through slots; means for regulating the flow of air passing through said slots in said wings, ailerons pivotally connected at the rear of said main wings, and 90 means in operative connection with said ailerons and said means for regulating the flow of air passing through said slots, to render the latter effective when said ailerons are lifted above normal angles. 95

3. In laterally controlling aeroplane flying machines, having wings projecting laterally from opposite sides of a central fuselage, 100 said wings having forwardly located auxiliary wings separated from the main wings to produce through slots; means for adjustably connecting said auxiliary wings relatively to said main wings, ailerons pivotally connected at the rear of said main wings, and means to operatively connect said aile- 105 rons to said auxiliary wings to regulate the flow of air through said slots in said wings and to cause interference of said air flow through said slots when said ailerons are lifted above normal angles. 110

4. In an aeroplane wing construction, in combination, a flap on the upper surface of the wing and slightly to the rear of the forward edge thereof, a trailing aileron adapted to operate in conjunction therewith and 115 means connecting said flap and aileron for raising them successively, adapted to increase the drag and decrease the lift on one side of the machine at low speed and large angles of attack on the main wing. 120

5. In an aeroplane wing construction, in combination, a flap on the upper surface of the wing and slightly to the rear of the forward edge thereof, a trailing aileron adapted to operate in conjunction therewith and 125 means connecting said flap and aileron for operating them successively adapted to increase the drag and decrease the lift on one side of the machine at low speed and high angles of attack on the main wing when the 130

aileron is raised beyond a predetermined point.

6. In an aeroplane wing construction, in combination, a movable flap extending adjacent the forward edge of the wing, a trailing aileron rearwardly of said flap, connections between said flap and aileron involving a lost motion connection whereby said aileron can be lowered without affecting the nose flap but will operate to raise the nose flap when said trailing aileron is raised a predetermined amount.

7. In an aeroplane wing construction, a normally inoperative air interceptor positioned adjacent the forward edge of the wing, a trailing aileron, means connecting said interceptor and aileron whereby raising of the aileron above a predetermined position will operate to bring the interceptor into operative position.

In witness whereof I have hereunto set my hand.

FREDERICK HANDLEY PAGE.
